UNITED STATES PATENT OFFICE.

ARCHER L. KNAPP, OF DETROIT, MICHIGAN, ASSIGNOR TO PACKARD MOTOR CAR COMPANY, OF DETROIT, MICHIGAN, A CORPORATION OF MICHIGAN.

DESIGN FOR A MOTOR-VEHICLE RADIATOR CAP.

Application filed June 6, 1928. Serial No. 27,017. Term of patent 3½ years.

To all whom it may concern:

Be it known that I, ARCHER L. KNAPP, a citizen of the United States, residing at Detroit, county of Wayne, State of Michigan, have invented a new, original, and ornamental Design for Motor-Vehicle Radiator Caps, of which the following is a specification, reference being had to the accompanying drawings, forming a part thereof, and in which—

Figure 1 is a top plan view of a motor ve-

hicle radiator cap incorporating my new design,

Figure 2 is a side elevation of the same, and Figure 3 is a rear elevation of the same.

I claim:

The ornamental design for a motor vehicle radiator cap, as shown.

In testimony whereof I affix my signature.

ARCHER L. KNAPP.
